UNITED STATES PATENT OFFICE.

JOHN JOSEPH GHEGAN, OF EAST ORANGE, NEW JERSEY.

ELECTRIC SIGNALING APPARATUS.

1,275,903.

Specification of Letters Patent. Patented Aug. 13, 1918.

Application filed April 12, 1917. Serial No. 161,416.

To all whom it may concern:

Be it known that I, JOHN JOSEPH GHEGAN, a citizen of the United States, and a resident of East Orange, in the county of Essex and 5 State of New Jersey, have made certain new and useful Improvements in Electric Signaling Apparatus, of which the following is a specification.

This invention relates to sounders for use 10 in Morse or code telegraph receiving stations, and the object is to provide a sounder that will operate on an alternating-current circuit, as, for instance, the sixty-cycle alternating current commonly supplied for 15 lighting and power purposes.

The sounder has a coil and preferably a magnetic core, the armature is pivoted to reciprocate through the polar field of such coil or magnet and to normally rest in a floating 20 position at a point of maximum magnetic density; this is the normal closed circuit position. The armature reciprocates or has a to-and-fro motion with fixed adjustable stops, to limit the extent of movement; it 25 also has a retractor, for this a quick-acting, helical spring is preferred. This spring is overpowered by the magnetism in the coil or magnet and under closed-circuit conditions the armature floats or rests, in a central position 30 where its free terminal or pole is coincident with the magnetic polar density point of the coil or magnet. When the current in the local circuit is broken or changed, the spring forces the armature or armature-bar 35 to impact or sharply strike a blow on the down-contact limit-stop and when the circuit is closed, the magnetism causes the armature to sweep or pass through the polar field so that its momentum causes an impact 40 with the opposite or up-contact stop; the armature instantly returning to an intermediate position, floats at the point of maximum polar density while the local circuit is closed, and continues to respond to code 45 signals, consisting of long and short impulses, as the Morse alphabet is transmitted over the main telegraph circuit.

In another application filed by me December 20, 1916, Serial No. 137,934, I have shown 50 and described relays and sounders adapted for use with alternating current in both main line and local circuits, and the present application shows and describes an improvement in structure of such a sounder.

55 In the drawings Figure 1 shows an alternating current circuit, a main telegraph

line and a local telegraph receiving circuit supplied with alternating current, and Fig. 2 shows the construction of the sounder.

In Fig. 1, *e* is an alternating current circuit supplied by the alternating current dynamo *g*; at the telegraph receiving station which is shown as a terminal station on the main telegraph circuit *o*, there is a relay *r* having front and back contacts 10 and 11, 60 a vibrating armature 9, and a retractor 12. A transformer is shown at *t*, with a primary coil *p* and a secondary coil *s*. This supplies light for the circuit 30 and also local battery current for the local circuit 8 controlled by 65 the circuit changer 9 of the relay *r*. The sounder magnet *m* has a polar projection 14, an armature *a* on a bar pivoted at 5 with up and down contacts 6 and 7; a compression spring 21 is adjustable by means of the 70 screw 20. As shown in Fig. 1, the local circuit 8 is closed at 10 and armature *a*, which, by reason of the separation between fixed contacts 6 and 7, is adapted to have a to-and-fro movement through the polar field of 75 magnet *m*, rests at the point of maximum polar density as shown. When circuit *o* is broken, armature 9 of relay *r* goes to its back contact 11, circuit 8 is broken, and spring 21 quickly forces the free terminal of the 80 armature-bar into engagement with the up-contact 6 with a sharp impact; when circuit 85 *o* is closed, armature 9 engages front contact 10, circuit 8 is closed, magnet *m* attracts its armature *a* against the power of spring 90 21, armature *a* sweeps through the polar field and its free terminal engages down-contact stop 7 with a sharp impact, armature *a* immediately returning to an intermediate position as shown in Fig. 1. This 95 described movement occurs when either a dot or a dash is transmitted, the difference in time closely following the excursion of the armature 9 of relay *r*.

What I claim is:

1. In a Morse sounder the combination of an electromagnet, a pivotally supported armature adapted to reciprocate through the polar field, an armature bar, a retractor for said bar and up and down contact stops for 105 said bar fixed in position to permit said armature and bar to reciprocate through the polar field, impact on the stop, and then take an intermediate position in the maximum polar field.

2. The combination in a Morse sounder for use in an alternating current local cir- 110

cuit of an electromagnet, an armature adapted to reciprocate through and across the point of maximum polar density, an armature bar therefor, a retractor for the 5 armature and two limit stops fixed in position such that the armature under closed circuit conditions passes through the point of maximum polar density to an extent permitting the bar to impact on a stop and then 10 return to an intermediate position, at the point of maximum polar density.

3. The combination in a telegraphic re-

ceiving instrument of an electro-magnet, a reciprocating armature contact, stops to determine the extent of motion of said contact, 15 a retractor for said contact, and means whereby said contact, under the momentum due to closing circuit in said magnet coil, moves through the polar field, impacts on one of said stops and instantly returns to 20 an intermediate position of maximum polar density in said field, out of engagement with either of said stops.

JOHN JOSEPH GHEGAN.
